UNITED STATES PATENT OFFICE.

GEORGE W. WHITEMAN, OF PHILADELPHIA, PENNSYLVANIA.

RAIL-FASTENING FOR METALLIC TIES.

No. 828,795.

Specification of Letters Patent.

Patented Aug. 14, 1906.

Application filed April 19, 1906. Serial No. 312,592.

To all whom it may concern—

Be it known that I, GEORGE W. WHITEMAN, a citizen of the United States, residing in Philadelphia, Pennsylvania, have invented 5 certain improvements in Rail-Fastenings for Metallic Ties, of which the following is a specification.

My invention relates to railway-ties, more particularly those made of metal, either built 10 up or of channel form, having an upper portion suitably arranged for supporting the rail, and to removable clips for use in connection with said tie for the purpose of securing the rail thereto.

15 My present invention consists of a form of fastening to be employed in connection with metal ties having a substantially flat upper surface, the general construction and arrangement of such fastening being shown in my 20 application for patent filed January 15, 1906, Serial No. 296,115.

My invention is fully shown in the accompanying drawings, in which—

25 Figure 1 is a perspective view of a metallic tie of the channel type having a rail mounted thereon which is secured by clips coacting with the tie and forming the subject of my invention. Fig. 2 is a plan view illustrating my present invention. Fig. 3 is a sectional 30 view on the line *a a*, Fig. 2. Fig. 4 is an inverted perspective view of the clip, and Fig. 5 is a plan view illustrating a detail of my invention.

In the structure of my former application 35 above referred to, wherein the removable clip is employed in connection with a metallic tie, provision is made for an abutment struck up from said tie, between which abutment and the flange of the rail the removable clip is disposed. The bolt securing the clip is passed 40 from beneath the web of the tie and serves to hold such clip in its adjusted positions.

In the present embodiment of my invention the top of the tie is slotted and the clips 45 are provided with depending lips entering said slots, the walls of which provide the desired abutment. These slots are cut at an angle with respect to the rail, so that the latter may be adjusted laterally in the direction 50 of the arrow *x* to take up the wear occasioned by the flanges of the wheel upon the inner face of the head.

In general respects the structure is similar to that of my former application, except as to 55 the character of the clip and abutment.

In the drawings herewith, 1 represents the

rail mounted on a metallic tie 2 of channel form. It will be understood, however, that ties of any form having a substantially flat upper portion or a portion directly supporting the rail, which may be slotted in the manner described, can be employed.

The tie is slotted at 3, such slots extending at an angle with respect to the rail, and the outer face or wall 4 of said slots forms an abutment. A movable clip 5, having a depending lip 6 fitting within this slot and bearing against the outer wall of the same, a portion 7, overlapping and bearing against the rail, and a serrated or notched upper portion 8, is provided to secure the rails to the ties, and one of these clips is used on each side of the rail. The clips are slotted at 9 for the reception of bolts 10, bearing a fixed relation to the tie, and the latter is slotted at 11 adjacent the slot 3 and in line with the length of the tie to permit said bolt to be let into the tie from the top, such slot 11 terminating in a portion 12 of narrower dimensions providing shoulders under which the head of the bolt is disposed. The clips are capable of lateral movement across the tie at an angle to the rail, with their lips within the slots and in engagement with the abutments to take up wear on the rail, such wear amounting in practice to about one-quarter inch on the inner side of the head. A notched or serrated washer 15 is provided to engage the notched or serrated face of the clip 5, and said washer is held in this engagement by a nut 16.

When it is desired to take up wear, it is only necessary to release the nuts, raise the washers 15, move the rail the desired distance laterally, and then move the clips along until they are wedged between the rail in its new position and the wall 4 of the slot 3, forming the anchor or abutment. After this is done the washer is replaced in its new engagement with respect to the clip and is fastened down against the latter by the nut 16, whereby said clip will be retained in the adjusted position, firmly holding the rail in place.

Instead of having a notched or serrated washer the clip may be notched or serrated on the bottom and the tie may be provided with complementary notched or serrated portions 17 adjacent the slots, forming the anchor or abutment, and this notched portion of the tie may be rolled therein.

The bolt in its engagement with the clip holds the latter in place, while the clip also

prevents the disengagement of the bolt from the tie.

I claim—

1. The combination of a metallic tie having a slot the wall of which forms an abutment, a rail, an adjustable member disposed between said abutment and the flange of the rail and overlying the latter, said member having a notched or serrated face, complementary notched or serrated portions carried by the tie, means for confining said notched or serrated portions in contact with each other, and a depending lip carried by the adjustable member and entering the slot formed in said tie.

2. The combination of a metallic tie for supporting rails having a slot the wall of which forms an abutment with an engaging face disposed at an angle with respect to the rail, an adjustable member disposed between said abutment and the flange of the rail and overlying the latter, a series of ribs or projections carried by said member, a series of complementary ribs or projections carried by the tie, means for confining said ribbed portions in engagement with each other, and a depending lip carried by the adjustable member and entering the slot in said tie.

3. The combination of a metallic tie for supporting rails having a slot the wall of which forms an abutment, an adjustable member disposed between said abutment and the flange of the rail and overlying the latter, said member having one of its faces notched or serrated, a series of complementary notches or serrations carried by another portion of the tie, means for confining said notched or serrated members in contact with each other, and a lip carried by said adjustable member and entering the slot in the tie.

4. The combination of a metallic tie for supporting rails, an abutment carried thereby formed by slotting the upper face of the tie and providing an angular wall, an adjustable member disposed between said abutment and the flange of the rail and overlying the latter, said member having one of its faces notched or serrated, a washer for engagement therewith having a series of complementary notches or serrations, means for confining said notched or serrated members in engagement with each other, and a lip carried by said adjustable member and entering the slot in the tie.

5. The combination of a rail-supporting tie, an abutment formed by slotting said tie and having an angular face, an adjustable member disposed between said abutment and the rail and overlying the flange of the latter, means fixed with respect to said tie for securing said member in its adjusted positions, and anchoring means carried by said adjustable member and entering the slot in the tie.

6. The combination of a rail-supporting tie, an abutment formed by slotting said tie

and having a face disposed at an angle with respect to the rail, an adjustable member arranged between said abutment and the rail and overlying the flange of the latter, said member being slotted, a bolt carried by the tie and having a fixed relation thereto and extending through said slot, means carried by said bolt for holding the rail-engaging member in its adjusted positions, and a lip carried by said adjustable member and entering the slot in the tie.

7. The combination of a rail-supporting tie, an abutment formed by slotting said tie and having a face disposed at an angle with respect to the rail, an adjustable member arranged between said abutment and the rail and overlying the flange of the latter, said member being slotted, a series of ribs carried by the upper face of said member, a bolt carried by the tie and having a fixed relation thereto and extending through the slot of the rail-engaging member, a washer ribbed to engage the surface of said rail-engaging member, means carried by the bolt for holding said parts together, and a lip carried by said adjustable member and entering the slot in the tie.

8. The combination of a rail-supporting tie, an abutment formed by slotting said tie and having a face disposed at an angle to the rail supported by said tie, a clip disposed between said abutment and the rail and overlying the flange of the latter, ribs or projections carried by said clip, said clip being slotted, a bolt carried by the tie and having a fixed relation thereto and passing through said slot, means carried by said bolt for engaging the ribbed surface of the clip to retain the latter in its adjusted positions, and a lip carried by said clip and entering the slot in the tie.

9. The combination of a rail-supporting tie, a pair of abutments formed by slotting said tie and having engaging faces paralleling each other but disposed at an angle with respect to the rail, adjustable clips disposed between said abutments and the flanges of the rail and overlying the latter, bolts carried by the tie and having a fixed relation thereto, said clips being slotted to permit movement with respect to the bolts, means carried by said bolts for confining the clips in their adjusted positions, and lips carried by said clips and entering the slots in the ties.

10. The combination of a rail-supporting tie, an abutment formed by slotting said tie, an adjustable clip disposed between said abutment and the flange of the rail and overlying the latter, means fixed with respect to the tie for confining said clip in its adjusted positions, and a lip carried by said clip and entering the slot in the tie.

11. An adjustable clip for securing rails to metallic ties, comprising a portion engaging the rail, a slotted portion for the passage of
